Dec. 13 22

Garrison Smith & Henry Brown, of Philadelphia, Penn.
Assignors to North Chase & North, of same place.
Letters Patent No. 1322, dated Oct. 9, 1860.

The schedule referred to in these Letters Patent and making part of the same.

To all whom it may concern:

It is known that we, Garrison Smith and Henry Brown, of the City and County of Philadelphia, and State of Pennsylvania, have invented or produced a new and original design for Stoves, and we, do hereby declare that the following is a full and exact description of the same, reference being had to the accompanying drawings, in which-

Des. 1322

Fig. 1. represents a bottom plate.

- 2. do. a top plate of the base.
- 3. do a side plate.
- 4. do a bottom plate of a crown top.
- 5. do an upper plate of a crown top.
- a. b. c. are mouldings.

What we claim as our invention and desire to secure by Letters Patent, is the design and configuration of the mouldings and ornaments, as herein described, forming an ornamental design for Stoves.
